UNITED STATES PATENT OFFICE.

THEODORE S. PIERCE, OF GRAND RAPIDS, MICHIGAN, ASSIGNOR TO
WILLIAM M. GRAY, OF ROMEO, MICHIGAN.

WASHBOARD.

SPECIFICATION forming part of Letters Patent No. 650,566, dated May 29, 1900.

Application filed March 9, 1897. Renewed April 26, 1900. Serial No. 14,355. (No model.)

To all whom it may concern:

Be it known that I, THEODORE S. PIERCE, a citizen of the United States, residing at the city of Grand Rapids, in the county of Kent 5 and State of Michigan, have invented certain new and useful Improvements in Washboards, of which the following is a specification.

This invention relates to washing-machines, and has for its objects, first, to provide improved means for rubbing the clothes to thoroughly effect the separation of the dirt from the clothes with the expenditure of but little labor and to combine therewith automatic means for feeding the soap to the clothes, and, 15 second, to provide the machine with an improved receptacle for holding the washed clothes while they are drained.

To these ends my invention consists in the features and in the construction, arrangement, and combination of parts hereinafter described, and particularly pointed out in the claims following the description, reference being had to the accompanying drawings, forming a part of this specification, wherein—

25 Figure 1 is a front elevation of my improved machine. Fig. 2 is a side elevation of the same. Fig. 3 is a vertical sectional view. Fig. 4 is a plan view of the soap-box, and Fig. 5 is a detail view of the means for feeding the soap-box up to the rolls.

Referring to the drawings, the numeral 1 indicates the frame of the machine, consisting of two upright sides 2 and a top or cross-piece 3, constructed in manner similar to the ordinary and well-known washboard. Journaled in the inner faces of the side pieces 2 of the frame are a plurality of rollers 4, which are arranged in the same straight plane to form a flat roller-bed. To the sides 2 of the 40 frame and near the upper ends of the latter are pivoted arms 5, which are free to swing about their pivots 6 and are longitudinally slotted throughout the greater portions of their length, as at 7.

45 The numeral 8 indicates a reciprocating rubber, which is adapted to be reciprocated over the rollers 4 and between the sides 2, the bottom or under side of the rubber being grooved or corrugated, as at 9 and as shown 50 in Fig. 3 of the drawings. To facilitate the movement of the rubber between the sides 2

and prevent it from binding, I journal in one end of the rubber antifriction-rollers 10, which have a roller-bearing against one of the sides 2, and to the opposite end of the rubber I affix 55 a spring 11, which has a yielding bearing against the adjacent side 2 of the frame. To the rubber are fixed uprights 12, to the outer ends of which is affixed a cross-bar 13, which forms a handle by means of which the rubber 60 8 may be reciprocated over the roller-bed. The ends of the cross-bar or handle 13 are reduced and project through the slots 7 in the arms 5 and are provided with heads 14, which project beyond the outer sides of the arms 5 65 and prevent the latter from spreading apart. On the reduced ends of the handle 13 are arranged rollers 15, (shown by dotted lines in Fig. 1,) which travel in the slotted portions of the arms 5 and render easy the movement of 70 the handle therein. The sides 2 of the frame are preferably rabbeted or recessed, as most clearly shown at 16, Fig. 2, for the reception of the arms 5, and to said sides are affixed springs 17, which bear against the under side of the 75 arms and produce an upward pressure thereon. Coiled springs 18 are arranged on the pivots 6 of the arms 5, the inner end of each of said springs being fixed on its pivot. The pivoted arms 5 act as levers in pressing upon the 80 springs 17. In the drawings the rubber 8 is shown as being near the center of the slots in the arms. The arms are pressed upward by the springs 17, and the spring 18 is placed so that its free end 21 presses neither up nor 85 down upon the pins or projections 19 and 20 on the arms when the rubber is in the position shown. If the rubber is moved outward toward the free ends of the arms 5, the free ends of the arms are lowered and the point 90 where the power is applied is carried outward, so that the arms 5 produce a greater pressure or leverage upon the springs 17, and the free ends of the springs 18 will now bear against the pins 19 and assist in supporting the same. 95 If the rubber is pressed toward the pivoted ends of the arms, the leverage or pressure upon the spring 17 is decreased, so that it would require greater pressure or power to depress it. The free ends of the arms 5 are 100 raised, which will cause the free ends of the springs 18 to come in contact with the pins

20, and after they reach that point the nearer the rubber is carried to the pivoted ends of the arms the greater will be the pressure of the free ends of the springs 18 upon the pins 20, thereby assisting in the downward pressure upon the arms. The springs 17 may be dispensed with, in which case the springs 19 may be set in position to press downward upon the pins 20 at all times, or they may be set in position to press upward on the pins 19 at all times, or, preferably, the springs 18 could be placed so that when the rubber is in the position shown they would press upon neither of the pins, in which case said springs 15 would have a tendency to lift the free ends of the arms when the rubber had passed from the position shown toward the pivoted ends of the arms. In order to produce the results above referred to, all that is necessary is to so fasten the springs 19 to the pivots of the arms that the free ends may bear in either direction required or may bear first in one direction and then in the other, depending upon the position of the arms.

25 Arranged beneath the rollers 4 is a soap-box 22, adapted to receive and retain a cake of soap. Said box may be constructed of any suitable material—as, for example, of wire, perforated sheet metal, or the like—and its 30 bottom is attached at its opposite ends to rods 23, which are arranged in tubular sheaths or guides 24, fixed transversely to the sides 2 of the frame. Fixed on the ends of the rods 23 are knobs or handles 25, the shanks 35 of which project through longitudinal slots 26 in the guides, and on the rods are arranged coiled springs 27, which bear at one end against the bottoms of the guides and at the other end against the knobs or handles, and 40 thus operate to lift the box-bottom toward the rollers 4 and keep the soap in contact with said rollers. The slots at their lower ends are deflected to one side, as at 28, so that by depressing the handles 25 and turning them into the deflected portions of the slots the box-bottom may be held away from and 45 out of contact with the rollers 4.

A soap-holder is also arranged on the rubber 8. This holder may conveniently consist 50 of a plurality of bent spring-arms 29, affixed at their ends in the upper side of the rubber, and said holder serves for holding an extra cake of soap, which may be used by the operator for soaping such parts of the clothing by 55 hand as may be necessary.

A receptacle 30 is also provided for holding the clothes after they have been washed and to permit the water to drain off from them. This receptacle may be formed of any suit- 60 able perforated or previous material and is preferably fastened at its bottom to a trans- verse rod 31, attached to the sides 2 of the frame and at its upper end to the upper end of the frame.

65 From the foregoing description the opera- tion of my improved machine will be readily

understood. The machine is placed in a wash-tub containing hot water in the same manner as an ordinary washboard, and the clothes to be cleaned are spread over the rollers 4 beneath the reciprocating rubber. The rubber is then pressed down upon the clothes and reciprocated back and forth by its handle, effectively rubbing or scrubbing the clothes, and the latter are thoroughly and automatically soaped by the soap held in contact with the rollers in the manner before described.

Having described my invention, what I claim is—

1. In a washing-machine, the combination 80 with a frame having a rubbing-bed, of arms each pivoted at one end to said frame and having longitudinal ways, a reciprocating rubber arranged to travel in said ways in the pivoted arms, and springs arranged to exert 85 an upward pressure on said arms, substantially as described.

2. In a washing-machine, the combination 90 with a frame having a rubbing-bed, of arms each pivoted at one end to said frame and slotted longitudinally, a reciprocating rubber, a handle fixed to said rubber and projecting at its opposite ends through said slots, heads on the ends of said handle operating to prevent the arms spreading apart and rollers 95 arranged on the ends of said handle and having a rolling bearing in the slots, substantially as described.

3. In a washing-machine, the combination 100 with a frame having a rubbing-bed, of arms each pivoted at one end to said frame and provided with longitudinal ways, a reciprocating rubber arranged to travel in said ways, and coiled springs fixed at their inner ends on the pivots of the arms and at their free 105 ends engaging said arms, substantially as described.

4. In a washing-machine, the combination 110 with a frame having a roller-bed, and reciprocating rubber, of a soap-box constructed to hold a cake of soap, means for holding the soap in yielding contact with the under side of the roller-bed, and means for holding the soap and soap-box out of contact with the roller-bed when the box is depressed, sub- 115 stantially as described.

5. In a washing-machine, the combination 120 with a roller-bed, of a soap-receptacle ar- ranged beneath the roller-bed, springs ar- ranged to hold the receptacle containing the soap so as to normally keep the soap in con- tact with the rollers, and means for lowering the soap-receptacle away from the roller-bed, substantially as described.

In witness whereof I have hereunto set my 125 hand and seal in the presence of two wit- nesses.

THEODORE S. PIERCE. [L. S.]
